DIVIDER FOR FILES

Benjamin G. Rand, North Tonawanda, N. Y.,
assignor to Remington Rand Inc., Buffalo, N. Y.

Application February 27, 1932, Serial No. 595,615

13 Claims. (Cl. 129—16)

The present invention relates to dividers for insertion in drawers of filing cabinets or like devices, and has particular reference to dividers adapted to normally retain filed material in vertical position, but constructed so that the dividers may be moved out of their normal position under tension during inspection of filed matter but will return to the normal position after the inspection and whenever they are free to move.

This invention provides an improved divider for insertion in drawers of filing cabinets or like devices for dividing a series of files into groups and also for use in place of the usual follower to hold filed material in a compact and upright position within the drawer; the top portions of the dividers being movable relative to the top of the index drawer so that the material held in the drawer is readily separable for inspection by a filing operator or clerk without the necessity of removing part or all of the material from the drawer, and after such inspection will move separated material from angular position automatically back to an upright and compact position.

In the drawings:

Fig. 1 is a cross-section of a drawer of file container with the divider of this invention applied in operative position therein.

Fig. 2 shows an enlarged detail view partly in section of one of the retaining members attached to a portion of the panel.

Fig. 3 is a disassembled perspective with portions broken away and shown in section showing a retaining member and panel-attaching means and their method of assembly.

Fig. 4 is an enlarged view in perspective showing a portion of one of the panel retaining strips.

Fig. 5 is a fragmentary cross-section through a drawer showing a modified form of divider.

Fig. 6 is a fragmentary cross-section through a drawer showing another form of the invention.

Fig. 7 is an enlarged view in perspective of the panel attaching member of Fig. 5.

Fig. 8 is an enlarged view in perspective of the attaching means of Fig. 6.

Fig. 9 is a fragmentary view in perspective showing part of the side wall of the drawer shown in Fig. 5 formed to receive the attaching means on the panel.

Fig. 10 is an enlarged fragmentary view in perspective showing a portion of the side wall of the drawer of Fig. 6, which is formed in a slightly different manner from Fig. 9 for receiving the attaching means on a divider.

A drawer or other container for receiving cards

or correspondence files in vertical position is indicated generally at 11, having sides 12 and a bottom 13. The bottom is formed with a pair of longitudinally extending offset portions 14 to provide channels 15 adjacent the sides and a central channel 16 in the center in the usual manner. Retaining and spacing strips 17, extending longitudinally of the drawer, are secured to offset portions 14 and are formed with a series of transverse slots 18 as shown in Figs. 1 and 4. The free ends of strips 17 extend upwardly as shown at 19 and are secured to the front and back walls of drawer 11.

A divider 20, in the form of a substantially rectangular sheet-metal plate, has a pair of projections 21 on the lower edge for engaging in slots 18 of strips 17. The divider 20 is held in adjusted position by this engagement of projections 21 and slots 18 and may then be rocked back and forth to allow inspection of the files it supports. This divider is normally held in a substantially vertical position by an anchoring and actuating device.

An outwardly extending finger 22 is formed on or attached to each end of the panel at a point thereon normally above the top of the drawer as shown in Fig. 1. Finger 22 is provided with a twisted end 23 formed with a slot 24 therein for engagement with means for retaining the panel locked in the drawer, as will be made apparent hereinafter. A second finger 25 is attached to the panel and extends outwardly therefrom to provide anchoring means for a resilient attaching member, and to this end is provided with a twisted head portion 27 formed with side recesses or notches 28 as shown in Figs. 2 and 3.

The anchoring and actuating device has an anchoring member 29 provided for engagement with fingers 22 and 25 for retaining and anchoring the panel within the drawer and to provide for the return thereof to an upright position should the panel be inadvertently or wilfully pushed from a vertical position in the drawer. In the form illustrated in Figs. 1, 2 and 3, member 29 comprises a back 30, side walls 31 and inwardly extending front flange portions 32 which provide guides entering the groove portions 28 of finger 25 and provide a retaining and protecting member for a coiled spring 33 attached to the end portion of finger 25 at one end, and to a pin 34 positioned at the lower end of member 29 at 50 the other end.

Ears 36 extending inwardly from side walls 31 of members 29 are adapted to engage head 27 and limit the upward movement of members 55

29 actuated by springs 33. Members 29 are guided in their movement on heads 27 through the sliding fit between flanges 32 in slots 28.

An upwardly extending tongue 37 is provided 5 upon the forward side of member 29 above the ears 36 for engagement with slot 24.

The fingers 22 and 25 on the panel or divider are arranged in such a relation that when members 29 are inoperative, either during adjustment 10 of the dividers in a drawer or during the detachment, storage or other handling of the dividers when detached from a drawer, the tongues 37 will be engaged in slots 24 and held in this position by the tension of springs 33. When members 29 are in operative position tongues 37 will 15 be normally disengaged from slots 24 as will be hereinafter described.

After inserting the panel in the drawer in such fashion that the downwardly extending members 21 formed on the lower edge thereof cooperate with an aligned pair of slots 18, a hook member 38 formed on the lower end of each anchor member 29 is engaged over the lower edge 20 of a strip 39 which extends longitudinally of the drawer upon the outer side thereof to form a slot, and has an offset flange to receive hook 38.

In this position each of the members 29 will have the tongue 37 below end 23 of finger 22 and member 29 will be free to rock relative to head 21 30 with flanges 32 guided in slots 28, springs 33 retaining members 29 engaged with strips 39, and the panel will have projections 21 held in engagement with slots 18.

When a divider and its anchoring members are 35 assembled in a drawer as shown in Fig. 1, the hooks 38 engaged with strips 39 hold tongues 37 free of engagement in slots 24, and springs 33 actuate panel 20 to normally hold it in a substantially vertical position. When the panel is in a vertical position as in Fig. 1, the head 21 lies 40 slightly above the ears 36. This operation of panel 20 by springs 33 will also move adjacent correspondence files or cards into a vertical compact filed position. When the files are to be inspected the operator or clerk can separate the files at any point by pushing the tops of adjacent files apart so the indexes or other inscriptions may be read. As the files are pushed apart by an operator the adjacent divider or dividers 45 will be operated so that panels 20 will rock or tilt about the lower ends of projections 21 engaged in slots 18. In this tilting or rocking movement of panels 20, anchor members 29 will be rocked about the hook connection with strips 39, flanges 32 will slide through notches 28, and springs 33 will be elongated and their tension increased. Upon release of the files by the operator, the springs 33 acting on the strips 39 through hooks 38 and on the panel 20 through connection 50 with head 21 will return panel 20 to vertical position together with those files that were rocked or tilted with the divider.

When it is desired to shift a divider, it is first necessary to disengage hooks 38 from strips 39, then tongues 37 are usually engaged in openings 24 to hold anchor members 29 in position. When this is complete, the whole divider may be readily removed from the drawer and replaced in any desired position for its usual operation by first positioning projections 21 in a pair of slots 18 and engaging hooks 38 with strips 39.

Another form of the invention is shown in Fig. 5 wherein a divider panel 20' is placed within an index drawer or the like and retained therein by 75 means of projections 21' which cooperate with

slots 18' of strip member 17' placed in the bottom of the drawer. This cooperation maintains the panel in a relatively fixed position with respect to the bottom of the drawer but permits relative rocking or tilting movement of the top of the panel longitudinally of the drawer. In order to permit longitudinal movement of the top of the panel a laterally extending finger 40 is attached to the panel for guiding and receiving the rod 41 in aperture 43 of the finger and for retaining one end of a coiled spring 42 which encircles member 41 and is connected to finger 40. The other end of the spring is fixed to the lower portion of the rod. It will be seen that in this form of the invention, relative movement of the 10 rod and finger is permitted so that when pressure is exerted upon the top of the rod 41, the distance between the bottom of rod 41 and finger 40 may be lengthened. The lower end of the rod is adapted to engage in a convenient portion of 20 the side wall of the cabinet drawer and retain the panel in position in the drawer. To this end, member 41 is provided with an inwardly extending portion 44 terminating in an upwardly extending tip 45 adapted to engage with a slot 46 25 formed in a recessed portion 47 of the side wall 12' of the drawer, as shown in Figs. 5, 7 and 9.

Since spring 42 is normally attached at one end to finger 40 and at the other end to the lower portion of the rod such as the inwardly extending portion 44, the tension of the spring retains panel 20' in an upright position in the file drawer, the operation being the same as that described for the structure shown in Fig. 1. Thus longitudinal movement of the top of the panel increases 35 the tension upon the spring 42 thus producing a longitudinal force component tending to move the panel into a vertical position.

In the form of the invention shown in Fig. 6, panel 20'' is provided with an apertured outwardly extending finger 48' in a position upon the panel which is normally above the upper edge of the side walls of the drawer in which the panel is inserted. The panel is provided with projections 21'' formed on the bottom edge thereof for 45 insertion in transverse slots 18'' formed in the strip member 17'' on the bottom of the drawer as explained more fully hereinabove.

A rod 50 is slidably engaged by the aperture of finger 48', a head member 52 being provided 50 thereon which serves as a stop and retaining member for the compressed coiled spring 51 which engages upon finger 48' at its other end. Rod 50 is provided with a shoulder 53 which limits the upward movement of rod 50 with respect to 55 the finger 48'.

Rod 50 is further provided with inwardly extending portion 54 adjacent the lower end thereof which is formed with an upwardly extending tip 55 for engagement with spaced slot members 60 56 formed in a beaded portion 57 of the side wall of the drawer.

In this form of the invention panels are inserted in the drawer by engaging the projections 21'' with the cooperating slots 18'' upon the bottom of the drawer and by pressing downwardly upon the heads 52 of the rods 50 so that inwardly extending portions 54 thereof will protrude into aligned slots 56 in the sides of the drawer and the tip portions 55 will contact with the side walls of 70 the drawer. Upon release of pressure upon the rod 50, the pressure of the coiled spring 51 upon the head of the rod and upon the finger 48' insures a sufficient force to urge the panel into an upright position within the drawer, a pivoting 75

or swinging movement occurring about the points of contact of the projections with the bottom of the drawer and at the points of contact of the portions 54 of rods 50 with the slots 56 in the side wall of the drawer, to retain the panel in a vertical position until it is moved from the vertical by an operator gaining access to the filed material contained in the drawer.

It is clearly seen that the present invention provides a divider for a file or like device which acts as a separator and support for filed material and may also be used as a follower and which further provides a file with means whereby the extensibility and flexibility of the filed material is insured.

The device further provides means within an index drawer, or like filing device, whereby filed material is caused to assume a neat, compact and upright position therein but may be easily displaced from the vertical position for inspection and may be readily removed from and replaced in the file drawer or container.

What is claimed is:

1. In a filing device, a drawer, a divider comprising a panel, means for detachably holding a lower portion of the panel in position in the drawer for rocking movement, anchoring members on opposite ends of the panel for detachable engagement with said drawer, and resilient means attached to said anchoring members and said panel for maintaining the panel in operative relation in the drawer and cooperating to normally move and retain said panel in a substantially vertical position in said drawer.

2. In a filing device, a drawer, a divider comprising a panel, means for detachably holding a lower portion of said panel in position in the drawer for rocking movement, anchoring members slidably mounted at opposite ends of the

panel and adapted to be detachably connected to the sides of the drawer, cooperating means on said members and the panel for limiting the movement thereof relative to the panel, and resilient means engaging said anchoring members and said panel for normally retaining the panel in the drawer in assembled relation with the panel normally and resiliently retained in a vertical position relative to the drawer.

3. In a filing device, a drawer, a divider comprising a panel, means for retaining a lower portion of said panel in position for rocking movement in the drawer, extensions on the sides of the panel above the top of the drawer, anchoring members engaged with said extensions and adapted to detachably engage with said drawer, and means for resiliently actuating said anchoring members to hold said panel in assembled operative relation with said drawer.

4. In a filing device, a drawer, a divider comprising a panel, means for holding the lower portion of the panel in adjusted position in the drawer for rocking movement, with resilient anchoring means connected to the upper portion of said panel and adapted to detachably engage the drawer, normally operable to hold said panel in a substantially vertical position.

5. In a filing device, a drawer, a divider panel, means for holding the bottom of said panel in position for rocking movement on the bottom of said drawer, a perforated extension member upon the panel, a rod extending through said perforation and formed with a tip to engage any one of a plurality of slots in the drawer, and resilient means engaging said extension

member and actuating said rod for holding the tip engaged in one of said slots.

6. In a filing device, a drawer, a divider comprising a panel, interengageable means on the lower edge of the panel and bottom portion of the drawer for detachably retaining the panel in an adjusted position in said drawer, said panel normally extending above the side walls of said drawer and having projections extending over and outwardly beyond the upper edges of said side walls, and resilient means connecting said projections and the side walls of said drawer to normally retain said interengageable means in engaged relation, and said panel substantially vertical in the drawer.

7. In a filing device, a drawer, a divider comprising a panel, means for detachably holding said panel in adjusted position in the drawer at the bottom portion thereof, an anchoring member slidably connected to each side of said panel above the side walls of said drawer, said anchoring members having detachable engagement with the side walls of said drawer, and resilient means engaging said panel and said anchoring members to retain said first-mentioned means and said anchoring members in engaged relation, and normally urge said panel to a vertical position in the file drawer.

8. In a filing device, a drawer, a divider panel, means for detachably anchoring said panel in the bottom portion of the file drawer for rocking movement relative thereto, a perforated extension member on the panel, a rod extending through said perforated extension and formed with a tip to engage any one of a plurality of slots in the drawer, and resilient means engaging said perforated extension and a portion of said rod to retain said tip in engaged relation with one of said slots.

9. In combination with a drawer of a filing device, a divider panel, an anchoring member slidably engaged with the panel, means on said anchoring member and said panel engageable to retain said anchoring member substantially parallel to the panel when said panel is disassembled from the drawer, said anchoring member having a part detachably connected to said drawer, and resilient means engaging said anchoring member and said panel for retaining said panel and drawer in assembled relation.

10. In a filing device, a drawer, a divider comprising a panel, supported on the bottom of the drawer for limited rocking movement in any one of a plurality of positions, and resilient means connecting the side portions of the panel to the drawer and normally urging said panel into a substantially vertical position in the drawer and into engagement with the bottom of the drawer for support thereon.

11. In combination, a drawer having a bottom and side walls, a panel, cooperating parts on the bottom of said drawer and panel for detachably holding said panel in any one of a plurality of positions in the drawer for rocking movement, a retaining member slidably mounted on each end of said panel, resilient means carried by each retaining member connected to said panel and normally actuating said retaining member to move it in one direction relative to the panel, and cooperating parts on said retaining members and the drawer for detachably connecting said retaining members to the drawer with said resilient means under tension, whereby said retaining means and resilient means will cooperate with said panel and drawer to nor-

mally urge said panel into a substantially vertical position.

12. In combination, a drawer having a bottom and side walls, a panel having a projection on the bottom, a strip mounted on said bottom and having a plurality of slots to selectively receive the projection on said panel, retaining members slidably and resiliently mounted on both ends of said panel and detachably connected to the sides of said drawer for normally urging said panel into an upright position and retaining said projection engaged in a slot in said strip.

13. In combination, a drawer having a bottom and side walls, a panel, means for holding the bottom of said panel in adjusted position on the

bottom of the drawer for limited rocking movement, and retaining members slidably and pivotally mounted on opposite ends of the panel, each retaining member comprising a channel-shaped member formed to provide a hook on one end to engage in a slot in the side wall of the drawer, and stop means adjacent the opposite end for limiting sliding movement of said member relative to the panel, and a resilient member housed in said channel-shaped member, connected thereto at one end and to said panel at the opposite end, said resilient member and retaining members cooperating to normally retain said panel in a substantially upright position in said drawer.

BENJAMIN G. RAND.
